THOMAS J. LOVETT, OF CHICAGO, ILLINOIS, ASSIGNOR TO COPPER PROCESS COMPANY, OF CHICAGO, ILLINOIS, A CORPORATION OF SOUTH DAKOTA.

CONCENTRATE-PREPARING MACHINE.

1,175,782.

Specification of Letters Patent. Patented Mar. 14, 1916.

Application filed November 14, 1912, Serial No. 731,455. Renewed January 20, 1916. Serial No. 73,182.

To all whom it may concern:

Be it known that I, THOMAS J. LOVETT, a citizen of the United States, residing at Chicago, in the county of Cook and State of Illinois, have invented a new and useful Improvement in Concentrate-Preparing Machines, of which the following is a specification.

This invention relates particularly to a concentrate-preparing machine, adapted to produce a granular concentrate and reduce the more friable gangue to a finely pulverulent condition, thus enabling the concentrate to be readily separated from the gangue. Such a machine is especially valuable for use in treating ores containing metals in fine, flaky particles. When such ores are treated, according to the standard methods now in use, by a stamping operation, much of the gangue is reduced to a slime, and at the same time the fine metal particles are freed from the rocky matrix in a condition closely approaching a slime, so that the metal particles will, in an effort to effect separation, float off with the slimes and thus be lost in the tailings.

The primary object of the present invention is to provide a machine of simple, durable construction and of high capacity which will operate upon a different principle from the mills now in standard use for treating ores of the character above referred to, and which will so prepare the concentrates or minerals, while reducing the gangue to a finely pulverulent form, as to enable the minerals to be readily separated from the gangue by any approved concentrating device.

A further object is to greatly reduce the cost of installation of mills for treating ores of the character referred to, and also to effect a large economy in milling operations.

It may be stated here that in the Lake Superior region there are known to exist vast bodies of ores containing free copper in fine, flaky condition. When such ore is reduced by the ordinary stamping process now universally employed, the fine metal particles are freed from the matrix, very

much of the gangue is reduced to the form of a slime, and the fine particles or minute scales of copper so closely approach the form of a slime that it is impossible to effect a high degree of saving, inasmuch as the metal particles will, in the effort to effect concentration, float off with the slimes and be lost in the tailings. The present invention obviates this difficulty, the improved machine herewith illustrated serving, while reducing the gangue to a finely pulverulent condition, to at the same time prepare or keep the concentrate in granular, slug or pellet form, so that it will readily sink in water, while the pulverulent gangue will be carried away with the water in the washing process.

The invention is illustrated in its preferred embodiment in the accompanying drawings, in which—

Figure 1 represents a plan view of a concentrate-preparing machine constructed in accordance with my invention; Fig. 2, an enlarged sectional view taken as indicated at line 2 of Fig. 1; Fig. 3, a plan view showing a lower rotary disk employed, with part of the sector-shaped wearing-plates thereof removed, this view showing also the bearings for the frame of the upper reciprocating pressure-plate employed; Fig. 4, a broken sectional view showing a disk equipped with an adjustable wrist-pin, or crank; Fig. 5, a broken section taken as indicated at line 5 of Fig. 4; and Fig. 6, a view of a modified form of one of the floating sections of the upper pressure-plate.

The invention is embodied, in the form illustrated, in a machine comprising a frame or base A; a rotary disk B; and a surmounting reciprocable member or pressure-plate C.

The disk B and member C are preferably disposed in horizontal planes. The ore is fed through a central opening in the reciprocating member C and is rolled between the lower surface of the member C and the upper surface of the member B. Thus, it will be understood that the member C serves both as a distributing member and as a pressure-member.

In the illustration given, the member B

comprises a circular base-portion 1 and surmounting, removable, sector-shaped wear-plates 2. The member 1 has its central portion provided with a hub 3 which carries an overhanging flange 4 having a beveled lower surface. The member 1 is also provided at its periphery with an upturned flange 5. The sectors 2 are provided at their inner points, or apices, with beveled lugs 6 which fit beneath the overhanging flange 4; and the sectors are provided near their curved outer edges with depending flanges 7 which fit within the flange 5.

The revoluble disk B has its base-portion fitted with a central post or stud 8 carried by a bearing 9. The post 8 serves to center the revoluble member; and the revoluble member is supported by conical rollers 10 carried by standards or bearings 11 and engaging an annular beveled track or rib 12 with which the member 1 is provided on its lower side. The member 1 is further provided with a bevel gear 13 which meshes with a bevel pinion 14 on a horizontally-disposed shaft 15 whose outer end is journaled in a bearing 16.

Beneath the peripheral portion of the rotary member B is located an annular trough 17 whose bottom inclines to a point 18 where is provided a discharge-chute 19, through which the gangue containing the prepared concentrates is discharged, ready for passage through a sluice, or over tables, or any other suitable concentrating device.

The reciprocable distributor and pressure-member C preferably comprises a hexagonal frame 20 having projecting guide-members 21 movable in bearings 22; and floating plate-sections 23, 23^a and 23^b confined within the hexagonal frame 20. The central plate-section 23 has a perimeter of hexagonal form and has upwardly convergent edges forming said perimeter. The plate-sections 23^a are preferably six in number, conforming to the perimeter of the member 23. The plate-sections 23^a have inwardly and upwardly sloping inner and outer edges. The plate-sections 23^b are preferably six in number and have their inner edges sloping inwardly and upwardly. The inner edges are of angle form—that is, are formed with reentrant angles 24 which conform to the angles of the perimeter formed by the outer edges of the plate-sections 23^a. Thus, the joints 25 between the plate-sections 23^a are staggered with relation to the joints 26 between the plate-sections 23^b.

The series of plate-sections are separated from each other by spaces 27, as shown in Fig. 2, thus providing for independent movement of the plate-sections, according to necessity, in the operation of the machine. The joints between the segments 2 of the wear-plates on the disk B are made tight in any suitable manner, as by the use

of solder; and the purpose of staggering the joints 25 with relation to the joints 26 is to prevent any materials from working along the joints and reaching the periphery of the rotary disk B without being subjected to the prolonged, progressive rolling action which is desirable to reduce the gangue to pulverulent form, free the metal particles from the matrix, and roll the metal particles into readily concentratable form. To enable the action just described to take place, the lower surface 28 of the reciprocable member C is substantially flat, and the upper surface of the rotary member B, afforded by the wear-plates 2, is correspondingly flat, thus providing for such close contact as will enable the concentrate, however small the pieces, to be rolled into granular form, while the gangue is reduced, by constant attrition of the upper and lower plates, as well as by mutual attrition of the pieces upon each other, to finely pulverulent condition.

The central section 23 of the member C is provided with a vertical perforation or feed-channel 29 provided at its lower end with a flaring or frusto-conical orifice 30 and equipped at its upper end with an elongated funnel or chute 31. Above the funnel 31 is a tube or ore-chute 32 adapted to deliver ore to the funnel. A water-supply pipe 33 has its discharge end adapted to deliver water to the funnel 31. Said pipe is equipped with a valve 34 adapted to control the amount of water delivered to the machine. The plate-sections 23^a are recessed on their upper surfaces as indicated at 35, and adapted to receive weights 36. The plate-sections 23^a are also equipped on their upper surfaces with loops or rings 37 adapted to serve as means for lifting or moving the plate-sections. The plate-sections 23^b are provided on their upper surfaces with recesses 38 adapted to receive weights 39. Loops or handles 40 are also provided to enable the plate-sections to be removed. The weights 39 are preferably much heavier than the weights 36 when it is desirable to provide for greater pressure per square inch at the outer plate-sections than is provided for at the intermediate plate-sections or the inner plate-section. The purpose in such case is to provide for a very gradual reduction of the ore-lumps, and finally for the reduction of the gangue to a finely pulverulent condition under the outer plate-sections, where a wider distribution of the materials and the finer granulation thereof occurs. It is under the outer plate-sections, in accordance with the preferred construction, that the final completion of the pellet-rolling action upon the minerals or concentrates is effected, the final reduction of the gangue to a finely pulverulent condition is accomplished, and the final

expressing of the fine gangue particles from the concentrates is carried to a conclusion. Ultimately, the fine-mesh gangue particles and the concentrates are, by the washing 5 action of the water, the centrifugal action of the rotary disk, and the reciprocating action of the upper presser-plate, carried beyond the periphery of the rotary disk, and, following the annular trough 17, are washed 10 out through the discharge-spout 19, ready to pass to the tables or other concentrate-separating devices.

It will be noted that the inward and upward slope of the inner edge-faces of the 15 intermediate plate-sections 23^a and outer plate-sections 23^b serve to insure a continuation of the progress of the materials toward the periphery of the member B. Also, it will be noted that the edge-surfaces of said 20 plate-sections are of sufficient size or extent along the incline to prevent materials from working wholly up through the spaces between the plate-sections. Again, it may be stated that the beveled contour of the lower 25 orifice of the feed-channel 29 insures the ore-pieces, even though the lumps may be of considerable size, passing with facility between the members C and B. The gradual reduction of the ore is begun beneath the 30 central plate-section 23, and the reduction is carried on progressively as the material is advanced toward the periphery of the member B.

In the illustration given, power is communicated to the rotary member B and the reciprocating member C from a shaft 41. The shaft 41 is equipped with a sprocket-wheel 42 which is connected by a sprocket-chain 43 to a socket-wheel 44 on the shaft 45. Another set of sprocket-wheels 42^a and 44^a, adapted to receive the chain 43, afford provision for varying the speed-ratio of the shafts 41 and 15. The shaft 41 is equipped with a disk 45, which, as shown in Fig. 4, carries an adjustable crank or wrist-pin 46. The wrist-pin or crank 46 is connected by a pitman 47 to the adjacent member of the hexagonal frame 20. It will be understood, therefore, that the throw of the reciprocating member C may be adjusted as desired; also, that the ratio of the oscillations or complete reciprocations of the member C with respect to the rotations of the disk B may be adjusted according to necessity. 50 Adjustments in the parts noted are desirable to regulate the work of a machine according to the character of the ore being treated. Thus, where the ore is of a very friable, easily-reduced character, adjustment is so made as to cause the materials to undergo the requisite rolling action and pass beyond the periphery of the rotary disk with great expedition. Thus, the output of the machine can be increased wherever the 55 friable character of the ore renders possible

a quick reduction with a consequent quick pellet-forming operation upon the metalliferous minerals. On the other hand, where the ore is more refractory, it is necessary to subject it to a more prolonged rolling 70 action between the extended surfaces, and the machine is adjusted accordingly to cause the discharge of the materials over the edge of the rotary disk only after the necessary reducing action has taken place.

The bearings 22 may be of any suitable form. As shown in Fig. 3, they are preferably provided with horizontal rollers 22^a upon which the members 21 rest, and vertical rollers 22^b adapted to confine the guide- 75 members 21 laterally, as shown in Fig. 1. This leaves the frame 20 free to adjust itself, while confining it sufficiently to insure proper reciprocation and to prevent the frame from being turned by the rotation of 80 the disk B. The plate-sections of the member C rest upon the rotary table or disk B and are free to move vertically with respect to the frame C, as has been indicated.

In operation, power is applied to the machine through a pulley 48, the power being taken from any suitable source. Power is communicated through the chain 43 to the shaft 15 which serves to rotate the disk B; and a reciprocating movement is imparted 90 to the member C through the medium of the crank 46 and pitman 47. The ore, preferably in the form of small lumps, or if desired, in quite finely divided form, is fed through the hopper 31 and the central 100 plate-section 23 of the member C. Water is admitted at the same time, by preference. The reciprocating member C serves as a distributing member and as a pressure-member. As the distribution occurs, the reduction of 105 the size of the ore-lumps is begun, and this reduction in size is progressively carried on as the materials are advanced toward the periphery of the rotary disk B. The centrifugal force developed by the disk B and also 110 the washing action of the water, tend to advance the materials toward the periphery of the rotary disk. The flow of water and the rotation of the disk are adjusted to suit the character of the ore being treated. As 115 the operation is carried on, the plate-sections 23, 23^a and 23^b of the reciprocating member C ride upon the pieces or particles of ore, and the ore-pieces are subjected to a 120 rolling or twisting action between the extended flat surfaces of the reciprocating and rotary members, under pressure, the weight of the upper plate-sections being adjusted according to the character of the ore being treated. The friable gangue constituents of 125 the ore-lumps are subjected to the continuous softening action of the water and to attrition due to the action of the reciprocating and rotary members and also to the mutual attrition of the ore-lumps; and at 130

the same time, the fine metal particles from the ore-lumps are pressed and rolled together, while the friable gangue constituents are being disintegrated and expressed 5 from the metal slugs or pellets which are being formed. Also, the pellets formed by the rolling action serve, in turn, to break up the finer ore particles and agglomerate the metal particles thereof with the metal 10 pellets. Thus, the rocky matrices which hold the metal particles are gradually broken down, and as the metal particles are freed, they are agglomerated with other particles and metal pellets, so that in the 15 end there results a concentrate comprising innumerable metal slugs, rodlets and pellets, but always in a granular form, or equivalent form, in which they are readily concentratable by any approved concentrating device. It may be added that the lumps and pellets operate like ball-bearings 20 between the reciprocatory and rotary members, thus reducing the friction, so that the machine actually operates under load with the expenditure of less power than when the machine is empty. It is noted, also, 25 that as the rolling action progresses, the pieces are rolled in ever-changing direction, and the pellets, constantly crossing the path of the other pellets, are rolled together or agglomerated, so that in the end many of 30 the pellets or slugs are of comparatively large dimensions, notwithstanding the fact that the metal particles may be almost 35 wholly or very minute dimensions as they occur in the rocky matrix.

The feature of employing a composite reciprocatory pressure-plate like that illustrated is of much importance for various 40 reasons. This expedient provides for the independent riding of each plate-section over the materials passing beneath it, so that the plates can adjust themselves to the varying 45 dimensions of the pieces passing beneath them. On the other hand, a certain continuity of the composite plate is provided 50 for by the employment of the sloping edges, which, while permitting a desirable independent movement, operate to prevent any 55 radical displacement of the plate-sections with relation to each other. Another advantage incident to the use of the independent 60 plate-sections is that it permits the ready removal and replacement of the plate sections, according to necessity. The plate-sections 65 may be composed of ordinary cast iron, or chilled iron, or steel. An advantage which the improved machine possesses is that these plate sections may be produced at a very low cost per pound, so that the 70 cost of maintenance of the machine may be quite low. The staggering of the joints 75 between the outer plate-sections with respect to the joints 25 between the intermediate 80 plate-sections insures that the materials shall

all be subjected to a rolling action, it being quite necessary that direct channels which might permit free passage of the materials shall be avoided.

The improved machine permits the practice 70 of a method of preparing concentrates which is nowhere in use, and which is wholly contrary to standard methods now employed. It is an important incident of the invention that it enables the milling of certain classes of ores to be effected by a gradual reduction throughout, thus obviating the use of stamps which operate in a violent manner, subjecting the working surfaces to tremendous blows which the best materials 80 which can possibly be employed in such machines are unable to withstand. Not only does the present invention reduce the cost of maintenance in milling operations, but it also very greatly reduces the cost of installation, since the very expensive steam stamps 85 which are now commonly employed in treating cupiferous ores, for illustration, are rendered wholly unnecessary in reducing finely impregnated rock; and re-grinding mills may be largely, if not wholly, dispensed with.

It may be added here that the ore may be advantageously prepared for passing through the machine herein illustrated by 90 using first an ordinary jaw-crusher to operate upon the large lumps as they come from the mine, and then using rolls to reduce the lumps to comparatively small size, ranging from the size of wheat to say $\frac{3}{4}$ " or 1 inch 95 size. If, however, it is desired to use the machine to operate upon tailings which have resulted from previous milling operations, and which contain high enough metal values to warrant their re-milling, the tailings may 100 be passed directly through the improved machine, which will operate as a concentrate-preparing machine, and will reduce the tailings to a condition in which the metal 105 values are practically all released from the 110 matrix and rolled into pellet or granular form, enabling ready concentration to be effected. At the same time, any free metal 115 particles which may remain in the tailings from previous milling operations will be 120 rolled into form suitable for ready concentration.

Fig. 6 shows a modified form of one of the intermediate plate-sections of the reciprocatory member C. This plate-section is 120 designated 23^d, and differs from the intermediate plate-sections 23^a in that it is provided with a vertical feed-channel 23^e, thus making provision for feeding materials 125 through the intermediate plate-sections. Such an expedient may be employed where the ore to be operated upon is of a very friable nature, so that it will be unnecessary 130 that the materials being treated shall be subjected to very prolonged rolling action.

Hence, in some instances, the capacity of the machine may be increased by employing auxiliary feed passages 23° at points removed from the axis of the member C.

5 It is noteworthy that the pressure-members of the machine have what may be termed extended area-contact surfaces between which the ore is rub-rolled in ever-changing directions as the surfaces shiftingly slide with relation to each other while the area-contact is maintained, so that the minerals will be freed and pellet-formed, that is, the mineral-pelleting action will occur. To this end, the pressure-members are 10 so disposed, proportioned and coöperatively moved, while maintaining substantially an extended area-contact, as to effect the desired preparation of the concentrate and finally discharge the materials with the 15 gangue in finely pulverulent condition and the minerals in readily concentratable form. It is evident that by controlling the washing action of the water through the machine, control of the output may be regulated to a considerable extent without changing the speed of the machine; also, the degree of comminution of the ore may be 20 regulated in the same way. The upper pressure-member may be regarded as one having 25 a floating central section encircled by a body floatable independently of the central section. In the illustration given, gravity gives the desired pressure between the floating sections and the revolving disk. From 30 Fig. 2, it will be understood that the inner or advance edge (edge first encountering ore-pieces) of each floating plate is beveled, or undercut, the slope being inwardly and upwardly, so that each floating section of the 35 upper presser-member will ride over the material as it is encountered. The improved machine may be used advantageously for reducing various ores to a fine degree of comminution, leaving the minerals in sufficiently 40 granular form to enable concentration to be effected with a high degree of saving. Moreover, the machine is economical in operation from the standpoint of power employed in 45 effecting comminution of the ore.

50 The weight of the floating plate-sections should be sufficiently great to effect a quick but gradual reduction of the ore-pieces, and such gradual reduction should result from the turning or rotating of the ore-pieces 55 between the surfaces of the upper and lower pressure-members. It follows that it is desirable to avoid such excessive pressure as might result in a sheer crushing of the material without the constant turning of the 60 particles which is desirable. A pressure of from eighty pounds to one hundred and twenty pounds per square foot, depending upon the nature of the ore, has been used with excellent results; and, in a machine 65 having a six-foot disk, it has been found

desirable to employ a speed of from thirty to fifty revolutions per minute, or upward, while employing a stroke of from eight to twelve inches for the upper pressure-member, the upper pressure member making 70 from thirty to fifty complete (forward and back) reciprocations per minute. The weight of the upper plate-sections, the speed of the machine, the length of stroke and the ratio of reciprocations to rotations may vary, but 75 the best results for any given class of ore may be readily determined in view of the foregoing explanation of the invention.

The construction described is simple, cheap, very efficient, and easy of maintenance. It provides for ready adjustment to suit varying conditions. The embodiment illustrated is shown by way of preference only, however; and the foregoing detailed description has been given for clearness of 85 understanding. Hence, no unnecessary limitation should be understood, but the appended claims should be construed as broadly as permissible in view of the prior art.

90 What I regard as new, and desire to secure by Letters Patent, is—

1. In an ore-reducing, concentrate-preparing machine, the combination of a pair of gangue-pulverizing mineral-pelleting pressure-members having substantially smooth extended area-contact surfaces, one of said members being a floating member, means for relatively reciprocating and rotating said members, and means for feeding ore-pieces 95 between said surfaces, said members so disposed, proportioned and coöperatively geared as to support and roll said ore-pieces 100 between them, finely pulverize the gangue, pellet-form the metals and 105 discharge the materials with the concentrate thus prepared.

2. In an ore-reducing, concentrate-preparing machine, the combination of a lower member having a substantially flat upper 110 surface, means for rotating said member, an upper floating distribution and pressure-member having a substantially flat lower surface adjacent said first-named surface, means for reciprocating said upper member, 115 and means enabling ore-pieces to be fed through said upper member and between said surfaces, said members so disposed, proportioned and coöperatively geared as to support and roll the ore, free and pellet-form the minerals, and discharge the materials.

3. In an ore-reducing, concentrate-preparing machine, the combination of a pair of gangue-pulverizing, mineral-pelleting pressure-members having extended area-contact surfaces adapted to be maintained in extended area-contact while being relatively shifted, one of said members being a floating member, means for feeding ore between 125 130

- 6 said surfaces, and means for imparting relative shifting and sliding movement to said members, said members being so disposed, proportioned and coöperatively geared as 5 to support and roll the ore between them in ever-changing directions, pellet the metals in the ore, and discharge the materials with the concentrate thus prepared from between said surfaces.
- 10 4. In an ore-reducing, concentrate-preparing machine, the combination of a pair of gangue-pulverizing, metal-pelleting pressure-members, one of said members having an upwardly presented extended area-contact 15 surface adapted to support the ore, and the other member being a surmounting floating member having a coöperating extended area-contact surface, means for feeding ore and water through the upper member, means for moving the lower member, and means for reciprocating said upper member across said lower member, said members substantially maintaining said area-contact during relative movement and 20 being proportioned and coöperatively geared to roll the ore in ever-changing direction between them, pellet-form the free metal and discharge the product from between said surfaces.
- 25 5. In an ore-reducing, concentrate-preparing machine, the combination with ore-feeding means and water-feeding means, equipped with means for regulating the water-flow, of a pair of gangue-pulverizing 30 mineral-pelleting pressure members having smooth, extended area-contact surfaces adapted to be maintained in extended area-contact while being relatively shifted, one of said members being a floating-member, 35 means for imparting relatively shifting, sliding movement to said members, said members being so disposed, proportioned and coöperatively geared as to support and roll the ore between them, pellet the minerals, and discharge the materials with the concentrate thus prepared from between said surfaces, and means receiving and collecting the discharged materials.
- 40 6. In an ore-reducing, concentrate-preparing machine, the combination with ore-feeding means and water-feeding means, having means for regulating the water flow, of a pair of gangue-pulverizing, mineral-pelleting pressure-members, one of said 45 members having an upwardly presented extended area-contact surface adapted to support the ore, and the other member being a surmounting floating member having a co-operating extended area-contact surface 50 and having also a passage through which the ore and water are admitted between said surfaces, means for rotating the lower member, and means for reciprocating said upper member, said members substantially 55 maintaining said area-contact during relative movement and being proportioned, disposed and coöperatively geared to roll the ore between them, pellet-form the minerals and discharge the product from between said surfaces.
- 60 7. In an ore-reducing, concentrate-preparing machine, the combination of a pair of relatively-rotating, relatively-reciprocating, gangue-pulverizing, mineral-pelleting pressure-members having extended, substantially flat adjacent surfaces, means for varying the ratio between the rotations and reciprocations of said members, and means enabling ore-pieces to be fed between said surfaces, said members so disposed, proportioned and coöperatively geared as to support and roll the ore between them, free and pellet-form the minerals and discharge the materials.
- 70 8. In an ore-reducing, concentrate-preparing machine, the combination of a pair of relatively-reciprocating, relatively-rotating pressure-members having substantially smooth adjacent surfaces, means for varying the throw of the reciprocating member, and means enabling ore-pieces to be fed between said surfaces, said members so disposed, proportioned and coöperatively geared as to support and roll the ore, free and pellet-form the minerals and discharge the materials.
- 75 9. In an ore-reducing, concentrate-preparing machine, the combination of a lower rotary disk having a substantially flat upper surface, and an upper reciprocating distributor and pressure-member having a floating central section and an encircling body floatable independently of the central section.
- 80 10. In an ore-reducing, concentrate-preparing machine, the combination of a lower rotary disk, and a surmounting, reciprocating distributor and pressure-member having an ore-passage therethrough, said last-named member comprising relatively movable floating sections, for the purpose set forth.
- 85 11. In an ore-reducing, concentrate-preparing machine, the combination of a lower rotary disk, a surmounting, reciprocating distributor and pressure-member having an ore-passage therethrough, said pressure-member comprising a frame and relatively movable floating plate-sections confined therein, and bearings for said frame adapted to permit reciprocation of the frame and floating of the frame with relation to said disk.
- 90 12. In a machine of the character set forth, the combination of a lower rotary disk, and a surmounting, reciprocating pressure-member comprising relatively movable floating sections of varying weight per
- 95 100 105 110 115 120 125

square inch, said members being disposed, proportioned and coöperatively geared to support and roll the materials between them in ever-changing direction and effect gradual reduction of the materials.

13. In an ore-reducing, concentrate-preparing machine, the combination of a lower rotary disk, and a surmounting, reciprocating distributor and pressure-member comprising relatively movable floating sections, one of the sections having an ore-passage therethrough, said members so disposed, proportioned and coöperatively geared as to support and roll the ore, reduce the gangue to pulverulent form and prepare the concentrate, for the purpose set forth.

14. In an ore-reducing, concentrate-preparing machine, the combination of a pair of relatively-rotating, relatively-reciprocating pressure-members, having substantially flat adjacent surfaces, one of said members comprising an angular frame and a plurality of relatively movable floating plate-sections therein, one of said sections having an ore-passage therethrough, said members coöperating to reduce the gangue to pulverulent form and prepare the concentrate, for the purpose set forth.

15. In an ore-reducing, concentrate-preparing machine, the combination of a lower rotary member having a substantially flat upper surface, and a surmounting, reciprocating pressure-member and distributor having a substantially flat lower surface, said second-named member comprising a plurality of relatively movable floating sections having their inner edge faces beveled for the purpose set forth.

16. In an ore-reducing, concentrate-preparing machine, the combination of a lower rotary disk having a substantially flat upper surface, and a surmounting, reciprocating pressure-member having a substantially flat lower surface, said last-named member comprising a floating central section and other relatively movable floating sections grouped about the central section, said members coöperating to reduce the gangue to pulverulent form and prepare the concentrate, and discharge the materials, with the gangue in such pulverulent form and the concentrate thus prepared, from between said members.

17. In an ore-reducing, concentrate-preparing machine, the combination of a rotating lower disk having a substantially flat upper surface, and a surmounting, reciprocating distributor and pressure-member resting on said disk, said second-named member comprising an inner angular section provided with an ore-passage, a plurality of intermediate sections grouped about the inner section, and a plurality of sections grouped about the intermediate sections,

said sections being relatively movable floating sections, and said members coöperating to reduce the gangue to pulverulent form, free the minerals and discharge the materials from between said surfaces.

18. In a machine of the character set forth, the combination of a lower rotary disk, and a surmounting, reciprocating distributor and pressure-member, comprising an angular central section provided with an ore-passage, a plurality of relatively movable intermediate sections encircling the central section and having outer edges forming an annular periphery, and a plurality of relatively movable sections encircling the intermediate sections, said third-named sections having reëntrant angles conforming to the angles of the perimeter formed by the outer edges of the intermediate sections.

19. In an ore-reducing, concentrate-preparing machine, the combination of a rotary lower member having a substantially flat upper surface, and a surmounting, reciprocating distributor and pressure-member having a substantially flat lower surface, said second-named member comprising a central section provided with an ore-passage, encircling intermediate sections, and sections encircling the intermediate sections, said sections being relatively movable and the joints between the intermediate sections being staggered with relation to the joints between the third-named sections.

20. In an ore-reducing, concentrate-preparing machine, the combination of a rotary lower member, and a surmounting, reciprocating distributor and pressure-member, said second-named member comprising a central section provided with beveled edges and provided also with an ore-passage, and independently floatable sections encircling the central section and provided with upwardly and inwardly sloping inner edges, said members coöperating to reduce the gangue to pulverulent form, prepare the concentrate in the manner specified, and discharge the materials from between said surfaces.

21. In an ore-reducing, concentrate-preparing machine, the combination of a rotary lower member, and a surmounting, reciprocating distributor and pressure-member comprising a central section provided with an ore-passage and having inwardly and upwardly sloping edges, independently floatable intermediate sections having inwardly and upwardly sloping inner and outer edges, and independently floatable sections grouped about said intermediate sections and having inwardly and upwardly sloping inner edges, said members coöperating to reduce the gangue to pulverulent form.

22. In a machine of the character set forth, the combination of a rotary lower member and a surmounting, reciprocating

distributer and pressure-member, comprising a central section having a feed-passage and provided with inwardly and upwardly sloping edges, independently floatable intermediate sections having inwardly and upwardly sloping inner and outer edges, independently floatable outer sections having inwardly and upwardly sloping inner edges and provided with reentrant angles conforming to the angles formed by the intermediate sections, said intermediate sections having end joints staggered with relation to the end joints of the outer sections.

23. In an ore-reducing, concentrate-preparing machine, the combination of a lower rotary disk, a surmounting, reciprocating distributer and pressure-member comprising a floating angular frame and a plurality of independently floating plate-sections within and conforming to said frame, one of said sections having an ore-passage therethrough, and bearings for the frame permitting reciprocation of the frame and permitting, also, floating of the frame, for the purpose set forth.

24. In an ore-reducing, concentrate-preparing machine, the combination of a pair of relatively-moving pressure-members having substantially flat adjacent extended area-contact surfaces, one of said pressure-members comprising a plurality of independently floating sections adapted to prevent passage of the ore, except as it is reduced between said extended area-contact surfaces, and means enabling ore-lumps to be fed between said surfaces, said members so disposed, proportioned and coöperatively geared as to support and roll the ore-lumps, reduce the gangue to pulverulent form, free the metal particles and roll them into slug or pellet form, and discharge the materials, with the gangue in pulverulent form and the concentrate thus prepared, from between said surfaces.

45 25. In an ore-reducing, concentrate-preparing machine, the combination of a pair of relatively-moving pressure-members having substantially flat adjacent extended area-contact surfaces, one of said members comprising a plurality of independently floating sections with an ore-passage through one of the sections, said sections adapted to prevent passage of the ore except as it is reduced between said area-contact surfaces, said members coöperating to effect gradual reduction of the ore-lumps, reduce the gangue to pulverulent form, free the metal particles and roll them into slug or pellet form, and discharge the materials, with the gangue in pulverulent form and the concentrate thus prepared, from between said surfaces.

26. In an ore-reducing, concentrate-preparing machine, the combination of a pair

of relatively-moving pressure-members having substantially smooth adjacent surfaces, means enabling ore-pieces to be fed between said surfaces, one of said members being disposed and adapted to support the ore-pieces thereon, and the other of said members comprising a plurality of relatively movable floating plate sections grouped and adapted to prevent passage of the ore except as it is reduced beneath said plate-sections, said members proportioned and coöperatively geared to reduce the gangue to pulverulent form, free the metal particles and roll them into slug or pellet form, and discharge the materials, with the gangue in pulverulent form and the concentrate thus prepared, from between said surfaces.

27. In an ore-reducing, concentrate-preparing machine, the combination of a lower disk having a substantially flat horizontal upper surface, means for rotating said disk, a surmounting, floating distributer and pressure-member having a substantially flat lower surface, means for reciprocating said surmounting member through such traverse that its edges move beyond the edges of said disk, and means whereby ore-pieces may be fed between said surfaces.

28. In an ore-reducing, concentrate-preparing machine, the combination of a pair of relatively-moving upper and lower pressure-members, the lower member having an upwardly-presented, substantially flat surface, and the upper member comprising a plurality of concentric groups of independently floating plate sections having flat surfaces resting upon the lower member, said plate-sections adapted to prevent passage of the ore except as it is reduced between the upper and lower pressure members, the outer ones of said sections having a greater weight per square inch of lower surface than the inner sections.

29. In an ore-reducing, concentrate-preparing machine, the combination of a pair of relatively moving upper and lower pressure members, the lower member having an upwardly presented substantially smooth surface, and the upper member comprising a plurality of rows of independently floating plate-sections resting upon the lower member, and having undercut advance edges, the joints between the plate-sections of one row being so staggered with relation to the joints between the plate-sections of another row as to prevent passage of the ore except as it is reduced between said pressure-members, and means for feeding ore-pieces and water between the pressure-members.

30. In a machine of the character set forth, the combination of a lower ore-supporting member having a smooth upper surface, means for imparting movement to said

member, a surmounting distributor and pressure-member having a smooth lower surface and comprising a plurality of independently floatable plates having undercut advance edges to facilitate the passage of ore beneath them, means enabling ore to be fed between said surfaces, and means for reciprocating said last-named member.

31. In a machine of the character set forth, the combination of a lower ore-supporting member having a smooth upper surface, means for imparting movement to said member, and a surmounting, reciprocating distributor and pressure-member having an ore-passage therethrough, said last-named member comprising relatively movable floating sections, for the purpose set forth.

32. In a machine of the character set forth, the combination of a lower member having a substantially flat upper surface, a surmounting distributor and pressure-member having an ore-passage therethrough, said last-named member comprising concentric groups of relatively movable floating plates, the joints between the plates of one group being staggered with relation to the joints between the plates of another group, and means for imparting relative reciprocating and rotating movements to said members.

33. In an ore-reducing concentrate-preparing machine, the combination of a pair of relatively-rotating, relatively-reciprocating pressure-members, having substantially smooth adjacent surfaces, one of said members comprising a frame and a plurality of relatively movable floating plate sections therein having undercut advance edges, one of said plate sections having an ore-passage therethrough, said members coöperating to reduce the gangue to pulverulent form and prepare the concentrate.

34. In a machine of the character set forth, the combination of a lower rotary member presenting a smooth upper surface, and an upper reciprocating pressure-member presenting a substantially smooth lower surface and comprising rows of relatively movable floating plate sections having undercut advance edges, the joints between the plate sections of one row being staggered with relation to the joints between the plate sections of another row, for the purpose set forth.

35. In a machine of the character set forth the combination of a lower ore-supporting member having a smooth upper surface, an upper distributor and pressure-member comprising a plurality of independently floatable plate sections having smooth lower surfaces resting on said first-named member, said sections having undercut advance edges and being arranged to prevent passage of the ore except as it is

reduced between said surfaces, means for producing relative movement of said members, means for feeding ore to the machine and means for collecting the gangue and concentrate as it is discharged from between said surfaces and discharging the same from the machine.

36. In a machine of the character set forth the combination of a lower ore-supporting member, means for imparting motion thereto, an upper distributor and pressure member comprising independently floating sections arranged about a common center and undercut at their inner edges and arranged to prevent passage of the ore except as it is reduced between the adjacent surfaces of said members, said second-named member having a central feed passage, means for shifting said second-named member with relation to said first-named member, ore feeding means and water feeding means discharging into said central feed passage, and means for collecting and discharging the gangue and concentrate from the machine.

37. In a machine of the character set forth, the combination of a lower rotary ore-supporting member having a smooth upper surface, an upper distributor and pressure member comprising a plurality of independently floatable sections having smooth lower surfaces resting on said first-named member, said sections being arranged and adapted to prevent escape of the ore except as it is ground between said surfaces, means for shifting the upper member with relation to the lower member, said sections of the upper member being arranged and constructed to overcome the tendency to rotate with the lower member, means for feeding ore to the machine and means for collecting the gangue and concentrate when discharged from between said surfaces.

38. In an ore-reducing, concentrate-preparing machine, the combination of a pair of gangue-pulverizing mineral-pelleting, pressure members having substantially smooth extended area-contact surfaces, one of said members being a floating member comprising a plurality of independently floatable plate-sections, means for relatively reciprocating and rotating said members, and means for feeding ore-pieces and water between said surfaces, said members so disposed, proportioned and coöperatively geared as to support and roll said ore-pieces between them, finely pulverize the gangue, pellet-form the minerals and discharge the material with the concentrate thus prepared.

39. In an ore-reducing, concentrate-preparing machine, the combination of a lower rotating disk having a substantially smooth upper surface, and a surmounting recipro-

cating pressure-member having a substantially smooth lower surface, said last-named member comprising a plurality of annularly arranged rows of independently floating plate-sections, supported on the rotary disk, said members co-operating to reduce the gangue to pulverulent form and prepare the concentrate and discharge the materials,

with the gangue in such pulverulent form and the concentrate thus prepared from between said members.

THOMAS J. LOVETT.
